LUDVIG T. PETERSEN, OF YOUNGSTOWN, OHIO, ASSIGNOR TO THE REPUBLIC RUBBER CORPORATION, OF YOUNGSTOWN, OHIO, A CORPORATION OF OHIO.

DESIGN FOR A TIRE-CASING.

57,260.

Specification for Design.

Patented Mar. 8, 1921.

Application filed September 7, 1920. Serial No. 408,786. Term of patent 14 years.

To all whom it may concern:

Be it known that I, LUDVIG T. PETERSEN, a citizen of the United States of America, residing at Youngstown, in the county of Mahoning and State of Ohio, have invented a new and ornamental Design for Tire-Casings, of which the following is a specification, reference being had to the accompany drawings, forming part thereof, in which—

Figure 1 is a plan view of my present design embodied in an automobile tire or casing; and

Fig. 2 is a transverse sectional view taken on the line 2—2 of Fig. 1.

It is to be understood, however, that my

said ornamental design is applicable not alone to casings, but is intended, and is equally well suited for the ornamentation of similar articles of manufacture having surface ornamentation, without in the least departing from my invention.

I claim:

The ornamental design for a tire casing substantially as shown.

In testimony whereof I subscribe my signature in the presence of two witnesses.

LUDVIG T. PETERSEN.
